Kenyon & Kenyon

UNITED STATES PATENT OFFICE.

ALFRED E. HORMAN, OF NEW YORK, N. Y.

ROTARY MECHANISM.

1,344,085.

Specification of Letters Patent. Patented June 22, 1920.

Application filed January 23, 1920. Serial No. 353,494.

To all whom it may concern:

Be it known that I, ALFRED E. HORMAN, a citizen of the United States, residing at New York city, county of New York, State of New York, have invented certain new and useful Improvements in Rotary Mechanism, of which the following is a specification.

My invention relates to rotary mechanism such as pumps and the like, and more particularly to rotary mechanism in which a rotor is mounted in a casing and provided with a wing movable relatively to the body portion of the rotor to permit continuous engagement of the wing with the interior of the casing during the rotation of the rotor. One of the objects of the invention is to reduce the power required to move the rotor and to adapt the mechanism for use at higher speeds than have heretofore been practical.

Another object is to provide a device of this character having a low starting torque.

A further object is to provide a construction in which leakage past the rotor is effectively prevented.

Other objects, features and advantages will appear more fully in the following detailed description and appended claims.

The accompanying drawing, forming a part of this specification, illustrates a pump containing one embodiment of my invention.

In the drawing,

Figure 1 is a section taken on line 1—1 of Fig. 2.

Fig. 2 is a section taken on line 2—2 of Fig. 1.

Fig. 3 is a section taken on line 3—3 of Fig. 1.

Fig. 4 is a detail view showing the rotor wing in elevation.

Fig. 5 is a section taken on line 5—5 of Fig. 4; and

Fig. 6 is a view in elevation of the exhaust valve.

Referring to the drawing, the rotor 1 is provided with shaft-like extensions 2 and 3 rotatable within bushings 4 and 5 respectively which are supported in extensions 6 and 7 of the casing 8 in which the rotor is inclosed. As shown in the drawing, the extension 3 of the rotor is formed on a disk-like member 9 which is secured to the portion of the rotor carrying the extension 2 by suitable means such as the screws 10. The casing as shown comprises a main portion having the extension 7 integral therewith

and a disk-like portion 11 which is secured as by bolts 12 to said main portion and has the extension 6 integral therewith.

As will be seen by reference to Fig. 1, 60 the rotor is arranged eccentrically within the casing, the cross section of the rotor at right angles to the axis of rotation being considerably less than that of the interior of the casing so as to provide a space 14 between the periphery of the rotor and the inside of the casing. The periphery of the rotor, as shown, engages the interior wall of the casing at the upper left hand portion, referring to Fig. 2, so that the opening 14 65 between the cylindrical periphery of the body portion of the rotor and the substantially cylindrical interior of the casing is of varying size between the inlet 15 and the outlet 16 of the casing. The body of the rotor has mounted thereon a wing 15^a which, as shown, is held retracted within a recess 16^a of the rotor when the latter is at rest. The means shown for holding the wing in its retracted position comprises a helical 70 compression spring 17 bearing on the rotor and on the underside of a suitable enlargement 18 on rod 19 projecting from the inner end of the body portion of the wing. The spring 17 tends to draw the wing inwardly 75 of the body portion of the rotor and is arranged together with the rod 19 on its enlargement 18 within a recess 20 in the body of the rotor. The said recess as shown is closed by a threaded closure 21 in the interior of which the enlargement 18 is slidably mounted. When the rotor is at rest all of the parts thereof are arranged within the cylindrical periphery thereof as shown in solid lines in Fig. 2. The advantage of 80 this construction is that when the pump is started there is no load thereon due to the engagement of the wing with the outer wall of the casing or due to the movement by the wing 15^a of the fluid, such as air or gas, 85 which the device is intended to pump.

As the speed of the rotor increases the centrifugal force acting upon the wing 15^a tends to move the latter into engagement with the peripheral wall of the casing and 90 when the desired predetermined speed has been reached, the wing will engage and remain in engagement with the said wall so that at this speed and higher speeds the rotor, including the wing, will force such air 95 or gas or fluid medium as has entered the space 14 out through outlet 16. During this

operation the centrifugal force acting upon the wing 15^a is partly counter-balanced by the spring 17 so that the latter tends to relieve the pressure of the wing 15^a upon the 5 interior or peripheral wall of the casing, thereby lessening the friction to be overcome in driving the pump and reducing the power required to move the rotor. By reason of this construction it is practical to drive the 10 pump at a much greater speed than where the centrifugal force upon the wing is not counter-balanced or counteracted.

I preferably also construct the apparatus so that the pressure of the wing upon the 15 wall of the casing, due to centrifugal force, is relieved by the pressure of the compressed fluid. To this end the wing is reduced adjacent its outer end so as to form a central portion 23 having a surface extending 20 longitudinally of the blade and adapted to engage the walls of the casing, there being also formed surfaces 23' on both sides of the surface 23. The surfaces 23' extend longitudinally of the wing and are spaced inwardly of the inner surface of the peripheral wall of the casing when the wing is in engagement with the said wall. The said surfaces 23' are desirably arranged at right angles to the radius of the rotor passing 25 through the center of the wing. With this construction it will be seen that the compressed fluid will always have access to at least one of the surfaces 23' and will exert on said surface a force tending to move the 30 wing inwardly of the body of the rotor, thus relieving the pressure of the wing on the peripheral wall of the casing without moving the wing out of engagement with said wall when the rotor is moving above 35 the desired minimum operative speed. The above advantage is obtained without any objectionable sacrifice of the strength of the wing.

In order to insure against the leakage 40 back to the inlet 15 of fluid which is being driven toward the outlet by the rotor I provide a large area of contact between the cylindrical body portion of the rotor and the interior of the casing. Referring to Fig. 2, 45 the upper left hand portion of the peripheral wall of the interior of the casing is curved upon an arc having the same radius as the body portion of the rotor, and the portion of said wall so curved is engaged 50 throughout its entire extent by the periphery of the rotor. As shown in the drawing, the body portion of the rotor is in engagement with the interior of the casing throughout an arc of approximately ninety degrees. 55 but it is to be understood that the extent of engagement may be varied to suit the requirements of each particular case. For reducing the friction between the body of the rotor and the interior of the casing I have 60 provided an oil duct 22 by which oil may be

fed as required to the contacting surfaces of the body portion of the rotor and the casing. The oil not only serves to lubricate the contacting surfaces but also assists in maintaining a tight seal between the body portion of the rotor and the casing at the area in question. 70

In order to facilitate the positioning of the rotor in proper relation to the casing and also to provide for the adjustment of 75 the rotor relatively to the casing in case of wear between the said parts, I have provided means whereby the rotor is mounted for adjustment toward or away from the peripheral inner wall of the casing. In the construction shown, the bushings 4 and 5 have their inner and outer surfaces eccentric with respect to each other so that by rotation of the said bushings the rotor is movable transversely to its axis. For moving the bushings 80 85 I have secured to each bushing a member, such as the screw 24, which projects through a slot 25, extending through the corresponding bearings 6 or 7 and permitting rotation of the said screws about the axis of 90 the bushing. As shown each screw 24 passes through a cover piece 26 arranged over the slot 25 and a washer of copper or other suitable material is arranged between the head of the screw 24 and the member 26. When 95 the screw is drawn tight, it is evident that the bushing will be held firmly in position in its bearing in the casing.

In assembling the mechanism after the rotor has been placed within the cylinder, the 100 rotor may be brought up into proper relation to the peripheral wall of the casing simply by movement of the screws 24 about the axis of the bushings. In case there should be wear between the body of the rotor and 105 the casing said parts may be brought into proper relation by simply loosening the screws, adjusting the rotor by means of the screws into engagement with the casing and thereupon again fixing the screws so as 110 to hold the bushing and the rotor in proper relation.

My invention also contemplates the construction of the wing 15 so that it will remain in close engagement with the end walls 115 of the casing. To this end the wing is provided with supplementary end wings 30, one at each end of the wing 15^a. These wings are movable relatively to the body of the wing 15^a so as to be adapted to be maintained in engagement with the end walls of the casing and may be held in engagement with said walls by any suitable means. In the construction shown the body portion of the wing is provided with passages 31 by means of which the air or other fluid which is being compressed by the pump is admitted to the backs of the supplementary wings 30 and 31 to yieldingly move the latter outwardly into engagement with the end walls of the casing. 120 125 130

As the portion of the supplementary wing 30 adjacent the outer ends thereof will have a path of movement longer than the inner portions of said wings for each rotation of the rotor, it will be seen that the wear toward the outer ends of the said supplementary wing will be greater than toward the inner ends. In order to compensate for this variation in wear, I have mounted the 10 supplementary wings so that upon movement toward the end walls the outer portion will move more rapidly than the inner portion. As shown in Fig. 4 the upper flange-like portion 32 of each supplementary wing has a curved upper and lower surface which fit between corresponding curved surfaces of the body of the wings, these surfaces being preferably curved on an arc about a center located approximately in the 15 axis of rotation of the rotor at a point in a line with the corresponding end of the wing. With this construction the supplementary wings will be movable toward the end walls of the casing at rates proportional to their 20 distances from the axis of rotation of the rotor and accordingly proportional to the wear on said wings.

To prevent the escapement of the compressed fluid between the rotor extensions 2 30 and 3 and the bushings in which they are mounted, I have, as shown, formed the inner surfaces of the bushings with circular grooves or recesses 33 containing a sealing medium such as oil. These grooves or recesses are preferably formed with walls 34 35 inclined outwardly and toward the axis of the rotor so that any of the compressed fluid seeking to escape between the extensions 2 and 3 and the bushings 4 and 5 will force 40 the oil or other sealing medium in the grooves 33 along the said inclined surfaces to a position to form an effective seal to prevent the escapement of the compressed fluid.

45 The outlet 16 is generally connected to a reservoir or other device in which there is a volume of the compressed fluid; and in order to prevent this compressed fluid from returning to the space 14, I provide a valve 50 35. I preferably construct this valve as a thin plate which may be made of steel or other suitable material. The plate is desirably not attached or secured in position being mounted so that when the depressed 55 fluid is forced through the outlet the valve lifts bodily, turning or tilting about one of its edges. The valve is normally held closed by the back pressure of the compressed fluid which has been forced through the outlet 60 port 36 past the valve. In order to insure the tilting of the valve as stated, the valve is mounted in an outlet passage which has projections 37 on both sides thereof, the lower surfaces 38 of these projections being inclined 65 downwardly toward and engaging the valve

at the edge about which it is designed to be tilted. The said surfaces 38 also serves as means to limit the upward movement of the valve. The valve, as shown, fits comparatively closely in the outlet passage of the 70 casing when in closed position; and in order to facilitate the flow of the compressed fluid past the valve when the latter is lifted from its seat, I have provided same with recesses 39 through which the fluid may pass, these 75 recesses being arranged in an edge portion of the valve at a point beyond the exhaust port 36 when the valve is closed.

While I have shown one embodiment of my invention it is to be understood that the 80 invention is not limited in all of its features to a pump or a compressor and that, furthermore, many modifications may be made without departing from the spirit of the invention.

Having thus described my invention what I claim and desire to secure by Letters Patent is:—

1. The combination of a casing, a rotor 90 therein comprising a body portion and a wing movable relatively thereto and engaging the interior of the casing, and yielding means connecting said body portion and wing tending to move said wing away from the wall of said casing.

2. The combination of a casing, a rotor 95 therein provided with a wing engaging the interior of the casing and movable transversely of the axis of rotation of the rotor, and spring means tending to counteract the 100 effect of the centrifugal force upon the said wing during the rotation of the latter.

3. The combination of a casing, a rotor 105 therein comprising a body portion and a wing movable into said body portion or outwardly therefrom into engagement with the interior of the casing, and means normally holding said wing retracted in said body portion.

4. The combination of a casing, a rotor 110 115 therein comprising a body portion and a wing movable into said body portion or outwardly therefrom into engagement with the interior of the casing, and means normally holding said wing retracted in said body portion, said means automatically permitting the movement of the wing into engagement with the interior of the casing when the rotor has attained a predetermined speed.

5. The combination of a casing, a rotor 120 125 therein provided with a wing engaging the interior of the casing and movable transversely of the axis of rotation of the rotor, and means comprising a spring tending to counteract the effect of the centrifugal force upon the said wing during the rotation of the latter.

6. The combination of a casing, a rotor 130 therein comprising a body portion and a

- 1 wing movable into said body portion or outwardly therefrom into engagement with the interior of the casing, and means comprising a spring normally holding said wing retracted in said body portion, said means automatically permitting the movement of the wing into engagement with the interior of the casing when the rotor has attained a predetermined speed.
- 5 10. 7. The combination with a casing, of a rotor therein provided with a movable member engaging an end wall of the casing and mounted for movement in a direction toward said wall at a greater rate at its outer 15 than at its inner end.
10. 8. The combination with a casing, of a rotor therein provided with a movable member engaging an end wall of the casing, different portions of said member being movable toward said wall at rates proportional 20 to their distances away from the axis of rotation of the rotor.
15. 9. The combination with a casing, of a rotor therein provided with movable members engaging end walls of the casing, different portions of said members being movable 25 toward said walls at rates proportional to their distances away from the axis of rotation of the rotor.
20. 10. In a fluid compressor, the combination with a casing, of a rotor therein provided with a wing engaging the wall of the 25 casing during the rotation of the rotor, said wing being acted upon by the compressed fluid in the casing to relieve the pressure of the wing against the said wall.
25. 11. In a fluid compressor, the combination with a casing, of a rotor therein provided with a wing engaging the wall of the 30 casing during the rotation of the rotor, said wing being reduced adjacent its outer end to provide a longitudinal surface adapted 35 to engage said wall and a longitudinal surface adapted to be acted upon by the compressed fluid in the casing to relieve the pressure of the wing against said wall.
30. In testimony whereof I have signed my 40 name to this specification.
- 45 ALFRED E. HORMAN.
